PRESSER SHOE

Marcus J. Maisen, Oak Park, Ill.

Application April 30, 1937. Serial No. 140,024

3 Claims. (Cl. 38—97)

This invention is an attachment for pressing-irons and may be termed a presser shoe.

The invention consists in the provision of a device to be applied to a pressing iron when the latter is used for pressing garments whereby a steaming of the garment during the pressing thereof may be accomplished to the end that the garment may be well pressed without becoming shiny, and at the same time, ironing cloth, sponge, and the like, may be eliminated to the end that the surface of the garment being ironed will at all times be visible to the person using the iron.

A further object of the invention is to provide a presser shoe that may be readily applied to the iron and which will be found, in actual practice, to enhance the use of the iron in ironing pleats.

The invention, together with its objects and advantages, will be best understood from a study of the following description taken in connection with the accompanying drawings wherein:—

Figure 1 is a side elevational view illustrating the application of the invention to an iron.

Figure 2 is a top plan view of the presser shoe with certain parts broken away.

Figure 3 is a bottom plan view of the shoe; and

Figure 4 is a transverse sectional view taken substantially on the line 4—4 of Figure 3.

Referring to the drawings by reference numerals it will be seen that the presser shoe indicated generally by the reference numeral 5 comprises a bottom plate 6 that tapers to a point at one end and is provided at opposite sides thereof with flanges which are provided so as to fit snugly against the sides of the iron at the sole plate of the latter as shown in Figure 1. The flanges 7 extend from the square or blunt end of the shoe to the pointed end of the shoe where said flanges are integral with a toe plate 8 that forms a toe boxing for the shoe to receive the pointed or toe end of the iron 9. In the present instance the iron 9 is shown as being an electric iron although it will be understood that the invention may be applied to other types of irons other than electric irons.

Fitting conformably in the bottom of the shoe 5 is a pad 10 of any suitable asbestos covered absorbent material. The pad 10 is confined between the bottom plate 6 of the shoe and a plate 11 of copper or the like which covers the entire top surface of the pad 10.

Plate 11 is provided so as to prevent the steam from escaping upwardly instead of penetrating

through the bottom of the shoe, with the result that the garment will receive the full effect of the steam. Also, plate 11 is provided with a depending flange 12 having its lower edge turned as indicated at 14, whereby to provide at the underside of the plate 11 and along the edges thereof a channel for receiving the marginal edges of the pad 10.

The plate 6 is provided adjacent the marginal edge thereof with relatively small perforations 13 while the main body portion of the plate is provided with relatively large perforations 15.

The flanges 7 adjacent the rear or heel end of the shoe are provided with apertured lugs 16 to which are connected the respective opposite ends of a coil spring 17 or analogous elastic member that is adapted to be disposed over the back or heel of the iron 9 as shown in Figure 1 so as to cooperate with the toe 8 for holding the shoe in proper position on the iron against longitudinal movement relative to the iron.

It will be seen that in applying the shoe 5 to the iron the iron is slid into the shoe from the largest or open heel end thereof so that the pointed end or toe of the iron fits into the boxing 8 after which the elastic element 17 is pulled upwardly to extend across the rear end of the iron to secure the shoe in position with the pressing surface of the iron resting properly on the plate 11.

With the shoe thus applied to the iron the manner of using the iron is as follows: the iron with the shoe associated therewith and the usual electric cord having its plug engaged with the electric socket of the iron 9, the iron with the shoe thereon is set into a basin of water, the depth of the water being relatively shallow. After the iron has remained with the shoe thus submerged in the water for a time sufficient for the absorbent pad of the shoe to absorb a reasonable amount of water the iron with the shoe thereon is withdrawn from the basin and set on the ironing table until the water in the pad starts to steam, when the pressing operation is then undertaken. As the iron with the shoe attachment thereon is slid over the garment being pressed, the steam penetrates the garment, thus eliminating, as is apparent, the use of a cloth to cover the garment heretofore resorted to, and also the use of a wet sponge or the like, which heretofore was employed for dampening the pressing cloth. Thus, with my attachment, the possibility of burning or scorch-

ing the garment being pressed is reduced to a minimum.

Having thus described the invention, what is claimed as new is:

- 5 1. A pressing shoe for attachment to an iron, said shoe comprising a flange plate having an edge contour corresponding to the edge contour of the body of an iron and being provided at one end with a toe boxing for receiving the toe end of the iron, said shoe having a perforated bottom plate, a metallic plate arranged in the shoe and having downturned edges supporting the last named plate in spaced relation above the perforated bottom plate of the shoe, and an absorbent pad confined in the shoe between said plates.
- 10 2. A pressing shoe for attachment to an iron, said shoe comprising a flange plate having an edge contour corresponding to the edge contour of the body of an iron and being provided at one end with a toe boxing for receiving the toe end of the iron, said shoe having a perforated bottom plate, a metallic plate arranged in the shoe and having downturned edges supporting the
- 15 20

last named plate in spaced relation above the perforated bottom plate of the shoe, an absorbent pad confined in the shoe between said plates, and an elastic element extending transversely of the shoe and connected at its respective opposite ends to the sides of the shoe to extend across the back of the iron to cooperate with the toe boxing to retain the shoe in position on the iron. 5

3. In combination, an iron, a shoe mounted on said iron and presenting a perforated bottom plate, an imperforate plate having downturned edges supporting the imperforate plate spaced from the bottom plate and having facial contact with the usual pressing surface or sole plate of the iron, said downturned edges having inwardly flanges defining channels and an absorbent pad confined between said perforated and imperforate plate with its edges seated in said channel; said imperforate plate serving to prevent the escape of steam upwardly from the 20 pad and thereby insuring the application of the steam, with full force and effect, to the garment being pressed. 10 15

MARCUS J. MATSEN.
